UNITED STATES PATENT OFFICE

133,943

DESIGN FOR A VITRIFIED TRAFFIC
MARKER

Dean R. Sever, New Philadelphia, and Donald J. Renkert, near Canton, Ohio; said Renkert assignor to The Metropolitan Paving Brick Company, Canton, Ohio, a corporation of Ohio

Application July 26, 1941, Serial No. 102,514

Term of patent 14 years

To all whom it may concern:

Be it known that we, Dean R. Sever and Donald J. Renkert, both citizens of the United States, residing respectively at New Philadelphia, in the county of Tuscarawas and State of Ohio, and at near Canton, in the county of Stark and State of Ohio, have invented a new, original, and ornamental Design for a Vitrified Traffic Marker, of which the following is a specification, reference being had to the accompanying drawing, forming part thereof.

Fig. 1 is a perspective view, from above, of the vitrified traffic marker showing our new design; and

Fig. 2 is a perspective view showing the bottom thereof.

Fig. 3, a fragmentary top plan view of the traffic marker showing the upper surface of the reflector projection; and

Fig. 4, a fragmentary side elevation of the upper central portion of the traffic marker showing one side of the reflector projection.

We claim:

The ornamental design for a vitrified traffic marker, as shown.

DEAN R. SEVER.

DONALD J. RENKERT.
